Primary Examiner — Cynthia Ramirez*Assistant Examiner* — Michael A Maharajh*(74) Attorney, Agent, or Firm* — Patrick J. Halloran(57) **CLAIM**

I claim the ornamental design for a face-lift massage device, as shown and described.

DESCRIPTION

FIG. 1 is a front perspective view of my new design of a face-lift massage device;

FIG. 2 is a rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The broken lines shown in the drawings are for the purpose of illustrating portions of the face-lift massage device that form no part of the claimed design.
